SLACK OR CUTTINGS REMOVING DEVICE
FOR KERF-CUTTING MACHINESWilliam T. McCullough, Chicago, Ill., assignor to
Goodman Manufacturing Company, Chicago,
Ill., a corporation of Illinois

Application November 5, 1942, Serial No. 464,594

4 Claims. (Cl. 262—30)

This invention relates to improvements in slack or cuttings removing devices for kerf-cutting machines, and more particularly to cuttings removing devices of the screw or helical conveyer type. The present application is a continuation in part of my Patent No. 2,320,004, dated May 25, 1943.

Among the objects of the present invention is to provide means to insure the positive feeding of the cuttings into the helical conveyer. A further object is to provide an angularly adjustable extension or discharge tube for the conveyor, having a conveyer element mounted therein for the full length of the adjustable portion of said tube, so that the cuttings can be positively discharged therefrom, at various angles including an upwardly inclined angle, and at a distance from the machine.

A still further object is to provide an arrangement for directing the discharge of the cuttings into a pile of loose material previously formed on the ground, so as to reduce the amount of coal dust released into the air.

The invention may best be understood by reference to the accompanying drawings, in which:

Figure 1 is a fragmentary plan view of the rear end of a kerf-cutting machine with a slack removing device attached thereto and shown in part horizontal section;

Figure 2 is a rear view of the machine on an enlarged scale, with parts of the slack removing device shown in section, and with the discharge spout in a different position of adjustment than shown in Figure 1;

Figure 3 is a vertical section taken on line 3—3 of Figure 1, showing details of the drive connections for the slack removing device;

Figure 4 is a plan detail view of the rotary sweep forming part of my invention;

Figure 5 is a fragmentary rear view showing a modified form of discharge spout in vertical section; and

Figure 6 is a fragmentary detail view showing the arrangement of the cuttings discharge spout so as to reduce the amount of coal dust released into the air.

Referring now to details of the embodiment of my invention illustrated in the drawings, the slack removing device is, in the main, of the same construction and arrangement as that disclosed in my prior Patent No. 2,320,004 previously referred to, so the main parts thereof may be described more or less generally, excepting as to those features which will presently be set forth as forming the subject matter of the invention.

The slack removing device is shown as applied

to a kerf-cutting machine 10 of conventional room and pillar type, including a main frame 11 having a cutter bar 12 projecting forwardly therefrom. As usual, a cutter chain 13 is driven about said cutter bar and operates in a cuttings channel extending beneath a motor 14 for the machine, and defined by side walls 15, 15 and a base plate 16. The cutter chain is driven by sprocket 17 suitably driven by the motor 14 so as to bring the cuttings rearwardly through the cuttings channel and discharge them at the rear end of the machine. A flexible feeding means may also be provided for the machine as usual, comprising a pair of winding drums 18, 18, also suitably driven by the motor and adapted to have flexible cables wound thereon and arranged to be anchored at suitable points adjacent the working face, to feed the cutter bar to the coal and along the coal face.

20 The slack removing device includes a tubular casing 20 extending transversely across the cuttings channel at the rear end of the machine. Said tubular casing has an elongated cuttings receiving aperture 21 on its inner side opposite and immediately adjacent the cutter chain sprocket so that the cuttings brought rearwardly by the cutter chain will be directed into the aperture 21.

The casing 20 may be connected to the mining machine frame in any suitable manner, which need not be described in detail. Said casing is arranged to close the rear end of the cuttings channel so that all of the cuttings must pass through and be discharged by the slack removing device.

30 Baffle plates 22 and 23 are suitably disposed in the cuttings channel at opposite sides of the cuttings receiving aperture 21 to assist in directing the cuttings into the latter.

40 The outlet end of the tubular conveyor casing 20 is provided with a discharge tube 25, herein consisting of an elbow 26 rotatably mounted on the end of said casing, and having an extension tube 27 secured thereto and arranged at an angle 45 to the axis of said tubular casing. The elbow is telescopically mounted on the end of said casing and has a bolt 28 removably inserted therethrough which extends into an annular groove 29 formed around the end of said casing so as to

50 permit the desired rotational adjustment of the discharge tube at varying positions. Thus said discharge tube can either be disposed horizontally at an angle toward the front or rear of the machine, or swung to any intermediate elevated angle, as desired. For instance, Figure 1 shows

it disposed at a rearward angle, and Figure 2 shows it at an elevated angle.

One of the principal difficulties heretofore encountered with screw conveyer cuttings discharge devices of the general type herein disclosed, is that of insuring the proper feeding of the cuttings into the conveyer so that they will be positively engaged by the screw and be discharged thereby. This is apparently due in a large measure to the fact that space limitations in a mining machine make it necessary to introduce the loose material into an open side of the conveyer tube, rather than into the top thereof, as is the preferred practice with conveyers of this kind. As a result, it has been found that in many cases the cuttings are not discharged satisfactorily, particularly with certain kinds of cuttings, which tend to become lodged in the rear end of the cutting machine in such a manner that only a relatively small percentage finds its way out of the screw conveyer, and the rest is dragged back into the kerf by the cutter chain.

I have found that this difficulty can be overcome, however, by providing a rotating agitator, or sweep, indicated at 30, which herein consists of a member having a hub 31 secured to the bottom of the cutter chain sprocket 17 as by a nut 32 and having four radially extending arms 33, 33. Said arms preferably extend horizontally in close relation to the base plate 16 with their extreme ends curved upwardly well beyond the reach of the cutter chain 13 so that they may extend into close proximity to the bottom edge of the cuttings receiving aperture 21 of the conveyer tube casing 20, as shown in Figures 1 and 3. It will be noted further in Figure 3, that the forwardly projecting baffle plate 23 which defines the upright edge of the discharge opening 21 at its discharge end, is disposed substantially tangential to the path of movement of said arms. Each of the arms 33 preferably has a relatively flat base 34 tapering towards its end and with an upright fin 35 running lengthwise thereof. With the rotating arms driven by the cutter chain drive shaft in this manner, I find that practically all the cuttings can be directed into and be carried away by the screw conveyer, in a much more positive manner than in previous devices.

Referring now more particularly to the flexible conveyer member which constitutes one of the principal features of the present invention, said member consists of two screw portions 40 and 41 rotatably mounted in the tubular casing 20 and the extension tube 27, respectively. The blade of the screw 40 is fixed on a tubular shaft 43 which is suitably driven at one end, as by a drive shaft 44 journaled in spaced apart anti-friction bearing members 45, 46 in a housing 47 which encloses one end of the tubular casing 20. The opposite, or discharge, end of the screw 40 floats freely in the casing 20 excepting for such bearing as may be provided by the edges of the screw blades.

The drive shaft 44 is operatively connected as usual to the motor 14 through suitable gearing which need not be described in detail, as it forms no part of the present invention.

The outer screw 41 is connected to the end of the screw 40 by a suitable flexible coupling, herein consisting of a universal coupling 49 connecting the outer end of shaft 43 of screw 40 to a shaft 50 and a second universal coupling 51 connected to shaft 52 of screw 41, so that the screw 41 is free to adjust itself in the extension tube in all of the various angular positions of the latter.

In the form shown in Figures 1 and 2, the screw 41 has bearing in the extension tube 27 by engagement of its blade edges in the latter.

In the modified form shown in Figure 5, the outer end of screw shaft 52 has bearing in a bracket 55 overhanging the extreme end of the discharge tube 27.

With the construction and arrangement of screw conveyer above described, the cuttings can be positively discharged in a more efficient manner than heretofore, particularly when the discharge tube 27 is adjusted at an elevated angle and it is necessary to elevate the cuttings to a considerable height.

A further disadvantage of coal cutting machines generally, and mechanical cuttings discharge devices in particular, is the large amount of coal dust which is discharged into the air as the cuttings emerge from the machine. Such air-borne coal dust is not only detrimental to the health of the miners, but constitutes a dangerous condition often leading to explosions in the mine.

It will be observed that with the arrangement of the discharge tube 25 shown and described, its outer end is normally free to rest by gravity on the mine floor, as the machine is slowly fed along the mine face. In practice, I find that the cuttings discharged at the end of said tube tend to form in a pile, as shown in Figure 6, which pile soon surrounds and completely covers the end of said tube. All subsequently discharged cuttings will then be deposited within the pile, to build up the latter from the inside, instead of being discharged directly into the open air. I find that due to this arrangement for controlling the cuttings discharge, the amount of free coal dust which finds its way into the air is greatly reduced, as compared with the usual form of coal cutting machine, either with or without a mechanical cuttings discharge attachment.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In combination with a kerf-cutting machine having a frame, a cutter chain, a cutter bar for said chain having a portion extending through a cuttings discharge passage in said frame, a drive member for said chain adjacent the rear end of said passage, a cuttings discharge device including a horizontally disposed casing in cuttings receiving relation at the rear end of said passage and having a screw conveyer element therein; a rotary sweep element mounted in said passage concentric with and below said chain drive member, including a plurality of propelling arms extending outwardly beyond the reach of said cutter chain into close proximity with said screw element to feed the cuttings directly to the latter, and means for driving said rotary sweep element in the same direction as said chain drive member.

2. In combination with a kerf-cutting machine having a frame, a chain carrying cutter bar having a portion extending through a cuttings discharge passage in said frame, a cuttings discharge including a horizontally disposed casing having an inlet opening at one side thereof for receiving the cuttings from said passage and discharg-

ing them at a distance from said machine, and a rotary sweep element mounted in said passage below said cutter bar, including a plurality of arms curving upwardly at their ends into close proximity with said inlet opening, and means for driving said rotary sweep element.

3. In combination with a kerf-cutting machine having a frame, a chain carrying cutter bar having a portion extending through a cuttings discharge passage in said frame, a cutter chain 10 on said cutter bar having a drive element adjacent the outlet end of said passage, a cuttings discharge device including a horizontally disposed casing in cuttings receiving relation at the outlet end of said passage and having a screw 15 conveyer element therein, and a sweep element mounted concentrically on and rotating with said drive element below said cutter chain, and having a plurality of propelling arms extending be-

yond the reach of said cutter chain into close proximity with said screw element to feed the cuttings directly to the latter.

4. In combination with a kerf-cutting machine having a frame, a chain carrying cutter bar having a portion extending through a cuttings discharge passage in said frame, a cutter chain on said cutter bar having a drive element adjacent the outlet end of said passage, a cuttings discharge device including a horizontally disposed casing having an inlet opening at one side thereof for receiving the cuttings from said passage and discharging them at a distance from said machine, and a sweep element mounted on and rotated by said cutter chain drive element adjacent the bottom of said passage and having a plurality of arms curving upwardly into close proximity with said inlet opening.

WILLIAM T. McCULLOUGH.
